PRESSURE OPERATED RESTRAINING DEVICE FOR FIRE EXTINGUISHING SYSTEMS

Harry B. Quarfoot, Chicago, and Henry Robert Harper, Evanston, Ill., assignors, by mesne assignments, to Reconstruction Finance Corporation, Chicago, Ill., a corporation of the United States

Application June 4, 1943, Serial No. 489,668

17 Claims. (Cl. 169—11)

This invention relates to pressure operated restraining devices for use in connection with fire extinguishing systems.

One particular use for a device constructed in accordance with the invention is in connection with fire extinguishing systems of the type in which carbon dioxide, employed as the extinguishing medium, is not normally contained in the distributing pipe, or pipes, but is supplied thereto for delivery to a fire only when a fire occurs. Such systems may be employed for the protection of rooms or other enclosures having closure-controlled openings such as doors, windows, and the like, which may be open normally, or at given times, but which should be closed in the event of the outbreak of a fire to confine therein the carbon dioxide vapors so that a fire extinguishing atmosphere may be created and maintained. Accordingly, any given closure may be subjected to any suitable force tending constantly to close the same, and a device constructed in accordance with the invention may be connected to a pipe of the system and with the closure so that it may hold the closure open as long as carbon dioxide is not supplied to the pipe and so that upon supply of carbon dioxide to the pipe the device is actuated to release the closure to permit the same to close. Alternatively, a device constructed and operating in accordance with the invention may in some instances be employed to hold a closure, or the like, normally closed and to release the closure for opening movement upon supply of carbon dioxide to the pipe with which the device is associated.

It is the primary object of this invention to provide a pressure operated restraining device which will normally function to hold a closure member in an open position, or in a closed position, and which will be actuated by the pressure of the fluid admitted to certain piping of a fire extinguishing system, or the like, to release the closure member so that it may be closed or opened, as the case may be, by another force relied upon to accomplish this latter result.

A still further important object of the invention is to provide a pressure operated restraining device of the above mentioned type which may be directly connected to a pipe of a fluid distributing system so that the device will be operated automatically by the pressure of the fluid when the latter is turned into the said pipe of the system, and which will function to prevent escape of the fluid from the pipe after the device has been operated.

With the foregoing and other objects in view,

which will become more fully apparent as the nature of the invention is better understood, the same consists in a pressure operated restraining device embodying the novel features of construction, combination and arrangement of parts as will be hereinafter more fully described, illustrated in the accompanying drawing, and defined in the appended claims.

In the accompanying drawing, wherein like characters of reference denote corresponding parts in related views,

Figure 1 is a longitudinal sectional view through a device constructed in accordance with the invention,

15 Figure 2 is an end view of the device,

Figure 3 is a cross section on the line 3—3 of Fig. 1,

Figure 4 is a plan view showing an adaptation of the device to a particular use; and

20 Figure 5 is a longitudinal section through the structure shown in Fig. 4.

Referring to the drawing in detail, 10 designates in Fig. 1 a pipe or conduit which normally

25 does not contain a fire extinguishing fluid under pressure, but which is intended to be supplied with such fluid only when a fire is to be extinguished. Various systems employing different types of fire extinguishing materials include such pipes or conduits and the device constituting the

30 subject matter of the present invention may be used in connection with any such systems for any one of a number of different purposes. Accordingly, while the invention will be described as embodied in a fire extinguishing system employing carbon dioxide as the extinguishing medium, it is to be understood that this is merely by way of example for convenience in explaining the invention and is not to be construed in any way as limiting its scope or its field of use.

40 In a fire extinguishing system employing carbon dioxide as the fire extinguishing medium, the carbon dioxide may be stored in a tank or in a bank of cylinders, and a distribution system, including the pipe 10, will extend from the tank to enclosures such as rooms where discharge nozzles are provided. Since the carbon dioxide is normally confined in a tank, or in cylinders, and is not delivered to its distributing pipes, including

45 the pipe 10, until a fire occurs, said pipes normally are not under pressure. In the event, however, of the outbreak of a fire in any given enclosure, a valve controlling the related distributing pipe 10 is opened for flow of carbon dioxide 50 from the tank through said pipe to the enclosure

for the purpose of creating a fire smothering or extinguishing atmosphere.

In order for the carbon dioxide best to perform its function of smothering or extinguishing a fire in an enclosure, the enclosure must be "flooded" with carbon dioxide vapor until the proper concentration is created, and this concentration must be maintained for a desired length of time. Therefore, if the enclosure includes doors, windows or the like, these, if open, should be closed as soon as possible following outbreak of the fire an initiation of delivery of the carbon dioxide into the enclosure.

The doors, windows or the like may be constructed and arranged to be closed by gravity, by springs or in any other suitable manner so that unless they are held open they will automatically assume their closed positions. A device constructed and operating in accordance with the present invention may be employed to hold the doors, windows, or the like, open as long as the pipe 10 is not under pressure, and may be relied upon to release the doors or windows to permit them to close whenever said pipe is supplied with the pressure fluid.

In accordance with the practical embodiment of the invention illustrated in the drawing, the present pressure operated restraining device comprises a short section of pipe 11 which is connected at one end to the pipe 10 in any suitable manner, as by means of a T-fitting 12, so that it is in constant communication therewith, and at its other end is partially closed by a suitable wall 13 such, for example, as the end wall of a cap 14.

Extending through the wall 13 is an opening 15, while insertable into this opening is a plug element 16 having extending laterally from its outer end an arm 17 to which is suitably fastened one end of a cable, rod, link, or the like, 18, the other end of which is designed to be operatively connected with a door, window or the like to hold the same open as long as the plug element 16 remains in the opening 15. By inspecting Fig. 1, it will be seen that the arm 17 is so shaped that its outer apertured end 17a lies in a horizontal plane that is indicated by the dotted line x. This horizontal plane intersects the plug 16 at a point which is intermediate the opposite ends of the opening 15 in which the plug is fitted. It will be apparent, therefore, that the line of pull, or force, delivered to the plug 16 by the cable, or the like, 18 through the arm 17 will cause the plug to bind against the side wall of the opening 15. As the door, window, or the like that is connected to the outer end of the cable 18 exerts a substantial force through the cable, it will require a substantial force to dislodge the plug 16 from the opening 15. Once the plug 16 is dislodged from the opening 15, the door, window, or the closure member, will be permitted to move to its desired closed position in response to the force which is relied upon to bring about this movement of the closure member.

To bring about dislodgement of the plug 16 from the opening 15, a combined plunger and valve member 19 is positioned within the bore of the short pipe section 11 so that the pressure of the fluid admitted to this pipe section will force the member 19 outwardly. A transverse pin 20 is passed through the pipe section 11 to act as a seat for the combined plug and valve member 19. This plug and valve member is provided with a stem 21 which is of less diameter than the di-

ameter of the opening 15 formed in the cap wall 13. When the combined plug and valve member 19 is forced outwardly by the admission of the pressure fluid to the pipe section 11, the stem 21 will engage the plug element 16 and will eject it from the opening 15.

To prevent leakage of the fire extinguishing fluid through the cap opening 15, after the plug element 16 has been ejected therefrom, the combined plug and valve member 19 is formed with a tapered valve seat 19a which will be forced into engagement with the edge of the inner end of the opening 15. Therefore, as long as the fire extinguishing fluid in the pipe section 11 is exerting its pressure against the combined plug and valve member 19, the tapered valve seat 19a will seal the opening 15 against the escape of the extinguishing fluid. After the feed of the extinguishing fluid to the distributing pipe 10 has been stopped and the fluid has been exhausted from the pipe 10 and the short section 11, the combined plug and valve member 19 will be permitted to return to its seat or rest 20 so that the stem 21 will be withdrawn from the cap opening 15. The door, window, or other closure member connected to the cable, or the like, 18 may then be moved to its normal position and the plug element 16 may be reinserted in the cap opening 15.

Figs. 4 and 5 illustrate a specific use for the pressure operated restraining device that has been described in detail in connection with Figs. 1 to 3 inclusive. This specific use is in connection with a carbon dioxide vapor pressure relief opening for an enclosed space which is to be flooded with vapor to create a fire extinguishing atmosphere. To be more specific, large electric motors, generators and alternators frequently are enclosed in housings for the purpose of permitting air to be circulated through the housings to cool such electrical devices. These enclosing housings are usually made of sheet metal and must normally be maintained air tight to prevent leakage of the cooling air.

When a fire starts in one of these large electrical devices, extinguishment of the same is usually accomplished by stopping the flow of cooling air through the housing, by closing shutters or valves in the inlet and outlet ducts leading to and from the housing respectively and then flooding the housing with carbon dioxide vapor to create a fire extinguishing atmosphere. This atmosphere must be maintained for a substantial length of time to prevent reignition during the period when the rotor is coming to a stop and the fire extinguishing atmosphere during the entire period must be maintained at a relatively high concentration of carbon dioxide vapor. The feeding of carbon dioxide vapor to the enclosing housing must necessarily build up a pressure therein and this pressure can become so great that it will burst the sheet metal walls of the housing if means are not provided to prevent the building up of an excess pressure.

It is the present practice to provide such enclosing housings with vent openings which are normally closed to prevent loss of the cooling air that is circulated through the housings. These vent openings are normally provided with closure devices that include a paper membrane or diaphragm which seals against the loss of the cooling air. These paper membranes or diaphragms, however, are ruptured when an excessive vapor pressure is built up in their enclosing housings. This paper membrane or diaphragm form of closure has not provided to be entirely satisfactory

because it is impossible to predict the pressures at which different paper membranes or diaphragms will rupture and the extent to which the paper membranes or diaphragms will be fractured or torn away when they do rupture.

Figs. 4 and 5 disclose a new type of vent opening structure for electrical equipment enclosing housings, or the like. The top wall of such a sheet metal housing is generally designated by the reference character 21. A conventional pipe flange 22 is applied to the margin of the opening 23 which is formed in the top 21 of the said housing. The opening 23 and the pipe flange 22 may be of any desired size to allow for proper venting of the housing that is provided with this vent opening structure. The pipe flange 22 is retained in place by means of the bolts 24 which pass through the reinforcing ring 25 located interiorly of the housing. A suitable length of piping 26 is threaded, or otherwise suitably connected, to the pipe coupling 22. Mounting brackets 27 are fastened to one side of the outer end portion of this pipe section 26 to receive the hinge pin 28. A cover or cap 29 is hingedly connected to the brackets 27 by the pin 28. A sealing gasket 30 is provided between the outer edge of the pipe section 26 and the inner face of the cover 29. The marginal portion of the cover 29, located opposite the hinge mounting for the cover, is provided with a leaf spring 31 that is connected at its outer end to a link 32.

In applying the pressure operated restraining device of Figs. 1 to 3 inclusive to this vent closure structure, the pipe section 11 of the said restraining device may be passed through the pipe section 26 of the vent closure structure so that its end cap 14 will be located exteriorly of the pipe section 26 and in alignment with the leaf spring 31. The plug element 16 will be mounted in the aperture of the cap 14 and will have its lateral arm 17 connected to the leaf spring 31 by the link 32. The combining plug and valve member 19 will be located within the capped end portion of the pipe section 11 and will be retained in operative relation to the apertured cap 14 by the transverse pin 20.

Figs. 4 and 5 disclose this vent closure structure in its normal condition; i. e., when the cover 29 is held in sealed engagement with the outer end of the pipe section 26 to prevent the escape of the cooling air that is normally circulated through the enclosing housing 21. This cover 29 is held tightly against the outer end of the pipe section 26 by the tension of the leaf spring 31. This spring is tensioned by placing the plug element 16 of the arm 17 in the aperture 15 of the cap 14. The tension of the spring 31 also loads the plug element 16 so that it will be retained in the aperture 15.

When a fire occurs within the enclosing housing 21 and the carbon dioxide extinguishing medium is delivered to the housing to create the desired extinguishing atmosphere, carbon dioxide is delivered to the pipe section 11. The pressure of this carbon dioxide acts upon the combined plug and valve member 19 to cause this member to eject the plug element 16 from the cap aperture 15. Displacement of the plug element 16 releases the cover 29 so that this cover may be moved away from its seat on the outer end of the pipe section 26 whenever sufficient vapor pressure is created within the housing 21 to overcome the weight of the cover. Suitable spring means, not shown, may be associated with the hinge structure for the cover 29 to load the cover so that a vapor pressure greater than that required to lift

the cover must be created within the housing 21 before the cover is unseated. It will be appreciated, therefore, that from the time the carbon dioxide vapor is turned into the enclosing housing 5 until the fire is extinguished, the cover 29 will function as a check valve to prevent excessive vapor pressure from building up in the enclosing housing 21. After the fire has been extinguished and the carbon dioxide flow to the enclosure has been stopped, the plug element 16 may be replaced in the opening 15 of the cap 14 and the cover 29 will again be held in its seated position against the outer end of the pipe section 26.

It is to be understood that the forms of this invention herewith shown and described are to be taken as the preferred examples of the same, and that various changes in the shape, size, and arrangement of parts may be resorted to without departing from the spirit of the invention or the scope of the subjoined claims.

Having thus described the invention, we claim:

1. A pressure operated restraining device for fire extinguishing systems, comprising a pipe section to be supplied with a fluid under pressure, a part of said pipe section having an opening therein, means including a plug element to be disposed in said opening to perform a restraining function, said plug element being designed to be ejected from said opening to release said restraining means when fluid under pressure is supplied to said pipe section, and means operable by fluid supplied to said pipe section to eject said plug element and close said opening against escape of fluid from said conduit when said plug element is ejected therefrom.

2. A pressure operated restraining device for fire extinguishing systems, comprising a pipe section to be supplied with a fluid under pressure, a part of said pipe section having an opening 40 therein, means including a plug element to be disposed in said opening to perform a restraining function, said plug element being designed to be ejected from said opening to release said restraining means when fluid under pressure is supplied to said pipe section, and a combined plug and valve within said pipe section operable by fluid supplied to said pipe section to eject said plug element and close said opening against escape of fluid from said conduit when said plug element is ejected therefrom.

3. A pressure operated restraining device for fire extinguishing systems, comprising a pipe section to be supplied with a fluid under pressure, a part of said pipe section having an opening 55 therein, means including a plug element to be disposed in said opening to perform a restraining function, and a combined plug and valve within said pipe section operable by fluid under pressure supplied to said pipe section to eject said plug element from said opening to release said restraining means and to close said opening against escape of fluid therethrough from said conduit.

4. A pressure operated restraining device for fire extinguishing systems, comprising a pipe section to be supplied with a fluid under pressure, a part of said pipe section having an opening 65 therein, means including a plug element to be disposed in said opening to perform a restraining function, and a combined valve and plug within 70 said pipe section to be moved longitudinally thereof by fluid under pressure supplied thereto to eject said plug element from said opening to release said restraining means and to close said opening against escape of fluid therethrough from said pipe section, said combined valve and plug having

a stem for engagement with the inner end of said plug element to positively eject the same from said opening when said combined valve and plug is moved longitudinally of said pipe section by the fluid.

5. A pressure operated restraining device for fire extinguishing systems, comprising a pipe section to be supplied with a fluid under pressure, a part of said pipe section having an opening therein, means including a plug element to be disposed in said opening to perform a restraining function, and means to eject said plug element from said opening to release said restraining means and simultaneously to close said opening against the escape of fluid therethrough from said pipe section by fluid under pressure supplied to said pipe section.

6. A pressure operated restraining device for fire extinguishing systems, comprising a pipe section to be supplied with a fluid under pressure, a part of said pipe section having an opening therein, means including a plug element to be disposed in said opening to perform a restraining function, means whereby fluid under pressure supplied to said pipe section acts to eject the plug element from said opening to release said restraining means, and means operable by the fluid to close said opening against escape of fluid therethrough from said pipe section when said plug element is ejected therefrom.

7. A pressure operated restraining device for fire extinguishing systems, comprising a hollow member in open communication with a distributing pipe line that is adapted to have a fire extinguishing medium delivered thereto under pressure, said member having an opening formed in a wall thereof, a plug element disposed in said opening and having an arm connected with an object to be restrained against movement, said arm being so shaped as to cause the force exerted through it while restraining said object to be applied to the plug element in a manner to bind and hold the latter in its opening, and means located in the hollow member to eject the plug element from its opening, for releasing the restrained object, when the extinguishing medium enters the hollow member.

8. A pressure operated restraining device for fire extinguishing systems, comprising a hollow member in open communication with a distributing pipe line that is adapted to have a fire extinguishing medium delivered thereto under pressure, said member having an opening formed in a wall thereof, a plug element disposed in said opening and having an arm connected with an object to be restrained against movement, said arm being so shaped as to cause the force exerted through it while restraining said object to be applied to the plug element in a manner to bind and hold the latter in its opening, and means located in the hollow member to eject the plug element from its opening, for releasing the restrained object when the extinguishing medium enters the hollow member and to close the opening in the hollow member to prevent escape of the extinguishing medium.

9. A pressure operated restraining device for fire extinguishing systems, comprising a hollow member in open communication with a distributing pipe line that is adapted to have a fire extinguishing medium delivered thereto under pressure, said member having an opening formed in a wall thereof, a plug element disposed in said opening and having an arm connected with an object to be restrained against movement, said arm being so shaped as to cause the force exerted

through it while restraining said object to be applied to the plug element in a manner to bind and hold the latter in its opening, and a combined plug and valve located in the hollow member and adapted to be actuated by the extinguishing medium delivered to the hollow member to eject the plug element from its opening and to then close the opening against the loss of extinguishing medium.

10. A pressure operated restraining device for fire extinguishing systems, comprising means forming an opening for venting excess vapor pressure from an enclosed space in which a fire extinguishing atmosphere has been created, a displaceable closure for said opening, a hollow member in open communication with the pipe line employed to deliver the fire extinguishing medium to the enclosed space, said member having an opening formed in a wall thereof, a plug element disposed in said opening and having an arm connected with the displaceable closure to restrain said closure against movement, said arm being so shaped as to cause the force exerted through it while restraining said closure to be applied to the plug element in a manner to bind and hold the latter in its opening, and means operated by the pressure of the extinguishing medium delivered to the hollow member to eject the plug element from its opening for releasing the closure.

11. A pressure operated restraining device for fire extinguishing systems, comprising means forming an opening for venting excess vapor pressure from an enclosed space in which a fire extinguishing atmosphere has been created, a displaceable closure for said opening, a hollow member in open communication with the pipe line employed to deliver the fire extinguishing medium to the enclosed space, said member having an opening formed in a wall thereof, a plug element disposed in said opening and having an arm connected with the closure to restrain the latter against movement, said arm being so shaped as to cause the force exerted through it while restraining said closure to be applied to the plug element in a manner to bind and hold the latter in its opening, and means located in the hollow member to eject the plug element from its opening, for releasing the closure, when the fire extinguishing medium enters the hollow member and to close the opening in the hollow member to prevent escape of the fire extinguishing medium.

12. A pressure operated restraining device for fire extinguishing systems, comprising means forming an opening for venting excess vapor pressure from an enclosed space in which a fire extinguishing atmosphere has been created, a displaceable closure for said opening, a hollow member in open communication with the pipe line employed to deliver the fire extinguishing medium to the enclosed space, said member having an opening formed in a wall thereof, a plug element disposed in said opening and having an arm connected with the closure to restrain the latter against movement, spring means interposed in the connection between the arm and the closure, said arm being so shaped as to cause the force exerted through it while restraining the closure to be applied to the plug element in a manner to bind and hold the latter in its opening, and a combined plug and valve device located in the hollow member and adapted to be actuated by the extinguishing medium delivered to the hollow member to eject the plug element from its open-

ing and to then close the opening against the loss of the extinguishing medium.

13. A pressure operated restraining device for fire extinguishing systems, comprising means forming an opening for venting excess vapor pressure from an enclosed space in which a fire extinguishing atmosphere has been created, a displaceable closure for said opening, a hollow member in open communication with the pipe line employed to deliver the fire extinguishing medium to the enclosed space, said member having an opening formed in a wall thereof, a plug element disposed in said opening and connected with the displaceable closure to restrain said closure against movement, said plug being designed to be ejected from said opening to release said closure, and means operated by the fire extinguishing medium supplied to the hollow member from said pipe line to eject said plug element and to close said opening against escape of the fire extinguishing medium from the hollow element when said plug element is ejected.

14. A pressure operated restraining device for fire extinguishing systems, comprising means forming an opening for venting excess vapor pressure from an enclosed space in which a fire extinguishing atmosphere has been created, a displaceable closure for said opening, a hollow member in open communication with the pipe line employed to deliver the fire extinguishing medium to the enclosed space, said member having an opening formed in a wall thereof, a plug element disposed in said opening and connected with the displaceable closure to restrain said closure against movement, said plug being designed to be ejected from said opening to release said closure, and a combined plug and valve within the hollow member operated by the fire extinguishing medium supplied to the hollow member from said pipe line to eject said plug element and to close said opening against escape of the fire extinguishing medium from the hollow member when said plug element is ejected.

15. A pressure operated restraining device for fire extinguishing systems, comprising means forming an opening for venting excess vapor pressure from an enclosed space in which a fire extinguishing atmosphere has been created, a displaceable closure for said opening, a hollow member in open communication with the pipe line employed to deliver the fire extinguishing medium to the enclosed space, said member having

an opening formed in a wall thereof, a plug element disposed in said opening and connected with the displaceable closure to restrain said closure against movement, said plug being designed to be ejected from said opening to release said closure, and a combined plug and valve within the hollow member to be moved longitudinally of the latter by the fire extinguishing medium supplied to the hollow member from said pipe line to eject the plug element and to close said opening against escape of the fire extinguishing medium from the hollow member when said plug element is ejected, said combined valve and plug having a stem for engagement with the inner end of said plug element to positively eject the latter from its opening when said combined valve and plug is moved longitudinally of the hollow member.

16. A pressure operated restraining device for fire extinguishing systems, comprising a pipe section to be supplied with fluid under pressure, a part of said pipe section having an opening therein, a plug element disposed in said opening and having an exterior arm adapted to be connected with a device to be restrained, said arm being so shaped as to cause the force exerted through it while performing its restraining operation to be applied to the plug element in a manner to bind and hold the latter in its opening, and means operated by the pressure of the fluid delivered to the pipe section to eject the plug element from its opening to release the device being restrained.

17. A pressure operated restraining device for fire extinguishing systems, comprising a pipe section to be supplied with fluid under pressure, a part of said pipe section having an opening therein, a plug element disposed in said opening and having an exteriorly positioned arm adapted to be connected with a device to be restrained, said arm being so shaped as to cause the force exerted through it while performing its restraining operation to be applied to the plug element in a manner to bind and hold the latter in its opening, and means operated by the pressure of the fluid delivered to the pipe section to eject the plug element from its opening to release the device being restrained and to close the opening in the pipe section to prevent escape of the fluid.
